UNITED STATES PATENT OFFICE.

HOMER A. SMITH, OF OAKLAND, CALIFORNIA.

DESIGN FOR AN ELECTRIC-LIGHT STANDARD.

No. 38,667.

Specification for Design.

Patented July 9, 1907.

Application filed May 29, 1907. Serial No. 376,454. Term of patent 3½ years.

To all whom it may concern:

Be it known that I, HOMER A. SMITH, a citizen of the United States, residing at Oakland, in the county of Alameda and State of California, have invented a new, original, and ornamental Design for Electric-Light Standards, of which the following is a specification.

Reference is herewith made to the accompanying drawing, forming part of this specification.

The figure is a vertical elevation of the electric light standard, showing my new design.

I claim:

The ornamental design for an electric light standard, as shown.

HOMER A. SMITH.
